UNITED STATES PATENT OFFICE.

ARTHUR M. WAITT, OF CLEVELAND, OHIO.

CAR-BUFFER.

SPECIFICATION forming part of Letters Patent No. 604,442, dated May 24, 1898.

Application filed September 21, 1897. Serial No. 652,448. (No model.)

To all whom it may concern:

Be it known that I, ARTHUR M. WAITT, a citizen of the United States, residing at Cleveland, in the county of Cuyahoga, State of Ohio, have invented certain new and useful Improvements in Car-Buffers; and I hereby declare the following to be a full, clear, and exact description of the same, reference being had to the accompanying drawings, in which—

10 Figure 1 is a plan view of a buffer embodying my invention. Fig. 2 is a longitudinal central section on the line 2 2, Fig. 1. Fig. 3 is a transverse section on the line 3 3, Fig. 2. Fig. 4 is a detail sectional view of portions of 15 the means employed for locking together the friction-plate socket and the friction-plate of the buffer. Fig. 5 is a plan view of a modification. Fig. 6 is a longitudinal central section of the modified devices on the line 6 6, 20 Fig. 5; and Fig. 7 is a transverse section of the modified devices on the line 7 7, Fig. 6.

Like symbols refer to like parts wherever they occur.

My invention relates to the construction of 25 that class of car-buffers wherein are combined a friction-plate socket, a telescoping friction-plate, and an interposed spring or springs, and has for its objects the simplification of the means for securing the friction-plate to 30 the friction-plate socket, so that the same cannot be tampered with or become separated while attached to the car, and the provision of means for augmenting the efficiency of the buffer-springs.

35 In carrying out my invention I combine the cup-shaped friction-plate and the friction-plate socket by means of a telescoping sleeve and bolt and means for preventing the rotation of the plate, and such a construction or 40 its equivalent embodies one feature of my invention.

In order to augment the efficiency of the buffer-spring, I combine therewith and with the friction-plate socket means for independently maintaining the spring under partial compression, and such a construction embodies a second feature of my invention.

45 There are other minor features of the invention, all as will hereinafter more fully appear.

I will now proceed to describe my inven-

tion more fully, so that others skilled in the art to which it appertains may apply the same.

In the drawings, A indicates the socket-casting, B the friction-plate, and C c the interposed springs.

55 The socket-casting A is provided at its center and bottom or at other suitable point with a bolt-hole 1 for the passage of a bolt 2, the same being countersunk, as at 1^a, for the reception and concealment of the nut 2^a of bolt 2, and the cup-shaped friction-plate B is provided on its inner face with a cylindrical socket or sleeve 3, into which the bolt 2 telescopes, the parts being prevented from separating by means of a key 4, which passes through the bolt 2 and slots 3^a of the sleeve 3, or by other suitable means.

60 In order to prevent any displacement or removal of the friction-plate B from the socket-casting A while the buffer is attached to the car, the bolt-socket 3 is preferably formed as a blind pocket—that is to say, does not open outward through the friction-plate— 65 and other means, such as the slots 3^a and key 4 or their equivalents, are provided for movably securing the bolt 2 in said socket 3.

70 In order to prevent the rotation of the cup friction-plate B with relation to the socket A, any suitable means may be provided—as, for instance, lugs a on the interior of the sockets and corresponding slots b in the telescoping portion of the cup friction-plate B—as 75 illustrated in the modification, Fig. 6; but for the purposes of the further invention hereinafter set forth I preferably prevent the rotation of the friction-plate B on the friction-plate socket-casting A by forming the latter with recessed projections 5, adapted to receive corresponding projections 6 on the periphery of the cup friction-plate B.

80 It will be noted that the means which is provided, primarily, to prevent the rotation of the friction-plate B on the socket A serves, secondarily, to prevent the tampering with 85 or disconnection of the friction-plate by rotation when bolts and nuts are the means employed for connecting the parts.

90 In buffers of this class there are commonly combined with the friction-plate nested spiral springs, the inner and lighter of which, c, exceeds the standard length and takes up the 95

initial shock, while the heavier or main stand-
ard-length spring assumes the load when the
lighter spring has yielded sufficiently for that
purpose. As is well understood, the resist-
5 ance of a spring is least effective during the
first stages of its compression. In order,
therefore, to be able to employ a standard
length for the lighter spring *c*, I provide the
friction-plate socket-casting *A* with a project-
10 ing seat or bearing *7*, the equivalent of which
would be a like bearing on the under face of
the friction-plate *B*, though said projecting
seat is preferably located in the bottom of
the socket *A*, as thereby it serves also to cen-
15 ter the heavier or main spring *C*.

In order to partially compress and confine
the heavier or main spring *C*, or that spring
which ultimately assumes the load, I provide
20 a series of anchors *8*, preferably *Z*-shaped
and of forged steel, adapted to take by one
hooked end under lugs *9* on the interior of the
friction-plate socket-casting *A* and by the
other over the exposed end of the main spring
25 *C*, and thus confine and partially compress
said spring. By reason of the recessed pro-
jection *5*, which also serves, in conjunction
with projection *6*, to prevent the rotation of
friction-plate *B*, the anchor *8* can be tilted
30 outward for insertion and inward to take over
main spring *C*, and when in final position and
the friction-plate *B* has been applied is held
from further outward movement by the pro-
jections or lugs *10* on the inner face of the cup
friction-plate *B*.

35 The construction of the devices being sub-
stantially of the character hereinbefore set
forth, they may be combined or the buffer set
up as follows:

The anchors *8* are placed in the socket-cast-
40 ing *A*, their lower hook ends under the lugs
9, with the anchors tilted outward to permit
the insertion of the main spring *C*. The main
spring *C* is next inserted and compressed the
desired amount, and the anchors *8* are then
45 tilted inward until the upper hooks take over
the spring *C*, when the spring may be released
and will be thereafter maintained in partial
compression by the anchors. The end of the
bolt *2* is inserted in the cylindrical socket or
50 sleeve *3* on the under side of the cup friction-
plate *B* and secured by passing the key *4*
through the slots *3a* in the sleeve and the slot
in the end of the bolt *2*. The lighter spring *c*
is placed in position in the friction-plate
55 socket *A* and the cup friction-plate *B* is finally
placed in position in the friction-plate socket
A and spring *c* compressed thereby until the
free end of bolt *2* passes through the bolt-hole
60 *1* in the bottom of socket *A* sufficiently to per-
mit the application thereto of nut *2a*, after
which, the compression of spring *c* being with-
drawn, the nut *2a* is drawn into the recess or
countersink *1a*, and when the friction-plate
65 socket *A* is thereafter secured to the car by
the usual bolts there can be no tampering
with the parts or removal of the cup friction-

plate *B* and springs *C c* without first remov-
ing the buffer from the car.

Having thus described my invention, what
I claim, and desire to secure by Letters Pat-
70 ent, is—

1. In a car-buffer, the combination with a
friction-plate socket, of a telescoping friction-
plate having a blind pocket inaccessible from
the exterior or bolt-socket on its interior face,
75 a bolt for securing the friction-plate to the
friction-plate socket, means for movably se-
curing the bolt in the bolt-socket on the in-
terior face of the friction-plate, a nut for the
bolt, and a nut-recess in the friction-plate
80 socket, substantially as and for the purposes
specified.

2. In a car-buffer, the combination with a
friction-plate socket having a countersunk
bolt-hole in its bottom, of a telescoping fric-
tion-plate having a slotted bolt-socket on its
interior face, a slotted bolt, and a key for
connecting the friction-plate and friction-
plate socket, substantially as and for the pur-
poses specified.

85 3. In a car-buffer, the combination with a
friction-plate socket or base and a friction-
plate or movable section, of a plurality of
buffer-springs and means for maintaining one
90 or more of said springs under partial com-
pression independently of the friction-plate
or movable section of the buffer, substan-
tially as and for the purposes specified.

4. In a car-buffer, the combination with a
friction-plate socket, a telescoping friction-
plate, and a plurality of buffer-springs inter-
posed between the socket and friction-plate,
95 of anchors for maintaining one or more of
said springs under partial compression with-
in the friction-plate socket and independ-
ently of the movable friction-plate, substan-
tially as and for the purposes specified.

100 5. In a car-buffer, the combination with a
friction-plate, and a friction-plate socket hav-
ing lugs on its interior, of interposed buffer-
springs, and *Z*-shaped anchors for holding
110 part of said springs under compression, sub-
stantially as and for the purposes specified.

6. In a car-buffer, the combination of a cup
friction-plate, and a friction-plate socket, one
115 of said parts having a raised spring-seat for
the inner or lighter buffer-spring, a plurality
of buffer-springs of equal length, and means
for maintaining part of said springs under
120 partial compression independently of the fric-
tion-plate, substantially as and for the pur-
poses specified.

7. In a car-buffer, the combination with a
socket having recessed offsets and anchor-
lugs on its interior, of a cup friction-plate
125 having lugs on its exterior which engage in the
recesses of the socket and interior lugs which
engage the spring-anchors, interposed buffer-
springs, and anchors which maintain one or
130 more of said buffer-springs under partial com-
pression, substantially as and for the pur-
poses specified.

8. In a car-buffer, the combination of a socket, a telescoping friction-plate, an interposed buffer-spring, and means for maintaining the buffer-spring under partial compression independently of the telescoping friction-plate, substantially as and for the purposes specified.

In testimony whereof I affix my signature, in presence of two witnesses, this 18th day of September, 1897.

ARTHUR M. WAITT.
